UNITED STATES PATENT OFFICE.

WILLIAM F. SMITH, OF POUGHKEEPSIE, NEW YORK, ASSIGNOR OF ONE-HALF TO
HERMAN A. SCHATZ, OF POUGHKEEPSIE, NEW YORK.

INTERNAL-COMBUSTION ENGINE.

Application filed May 23, 1924. Serial No. 715,338.

This invention relates to improvements in internal combustion engines, and particularly to gasoline engines of the so-called air cooled type.

5 The object of the invention is to provide a gasoline engine which is simple in construction and efficient in operation.

With this object in view, according to one of the features of the present invention, 10 gasoline or other fuel is supplied to the engine in a completely vaporized condition, the sprayed fuel being exposed to the heat of the engine, preferably by passage through a chamber in contact with the cylinder head. In order to increase the volumetric efficiency of the engine, the vaporization of the fuel takes place before it is mixed with air, whereby air reaches the cylinder head in a relatively cold condition.

15 In accordance with another feature of the invention a carburetor, controlling the delivery of varying amounts of fuel to the engine, is so arranged that irrespective of the quantity of fuel delivered to the engine, 20 the proportions of the fuel mixture remain constant. The carburetor herein disclosed is particularly adapted for mixing vaporized hydrocarbon with air.

In accordance with still another feature 25 of the present invention, in addition to the usual throttle, automatic means are provided which in response to the speed of rotation of the engine, control the quantity of fuel delivered thereto. In this manner 30 unnecessary racing of the engine is prevented.

Further features of the invention have to do with the cooling of the cylinder and cylinder head.

35 In accordance with the present invention fins or webs project from both the cylinder and the head, exposing a large surface to air drawn in by a blower. The construction is so provided that, as far as possible, 40 these fins are kept intact. The screws by means of which the head is attached to the cylinder, are at right angles to the vertical axis thereof, avoiding thus the necessity of cutting away cooling fins for the purpose 45 of giving access to such screws. The cylinder head is cast of substantially uniform thickness throughout. This cheapens the casting and insures rapid and uniform cooling of the head and uniform protection to 50 the valves. This result is enhanced also by

the manner in which the head is adjusted to the cylinder.

These and other features of the invention will more clearly appear from the following detailed description and the claims. 60 The invention is disclosed as applied to a one-cylinder gasoline engine, particularly adapted for use in tractors and the like. Obviously, the various features are readily applicable to internal combustion engines of 65 widely varying types without departing from the spirit of the present invention.

In the drawings Fig. 1 is a vertical cross-section of as much of a gasoline engine as is necessary for an understanding of the 70 various features of the present invention; Fig. 2 is a sectional view along lines 2—2 of a portion of Fig. 1; Fig. 3 is a plan view of a casting (131); Fig. 4 is a cross-section of the carburetor taken along a line slightly 75 to the right of 4—4 of Fig. 1; Fig. 5 is a similar view taken along lines 4—4 of Fig. 1 and showing a different adjustment of the carburetor; and Fig. 6 is a sectional view along lines 6—6 of Fig. 1. 80

Referring to the drawings, 1 is a cylinder provided with a plurality of annular webs or fins 2, entirely surrounding the cylinder and which serve as cooling surfaces. These fins are increasing in width as the head 3 is approached, whereby the cooling surface is varied, depending on the amount of heat to be dissipated. The cylinder head is also provided with annular cooling fins 4 and with other cooling surfaces to be hereinafter 90 referred to more in detail. Inasmuch as the heat developed is greater in the engine head, proper cooling thereof is of prime importance. The cylinder head is provided with apertures 5 and 6 through which two spark 95 plugs, such as 7, may be inserted. The fins or webs 8, 9 and 10 at the end of the cylinder 1, are so shaped that they form a seat for the head 3 and contact, in the order named, with a sloping wall 11 of the head and the inside 100 surfaces of fins 12 and 13. 12 and 13 are the last fins projecting from the head 3; the connection between the base of the fins and the head being by means of webs such as 14 and 15. Six or more of the webs 15 have screw-threaded holes with which screw-threaded lugs, such as 16, cooperate. The ends of the lugs 16 are tapered and are adapted to engage the correspondingly tapered lower surface of the web 9. In assembling the engine, 110

the sloping wall 11, wedged on the correspondingly sloping ring 8, insures a tight closure for the cylinder. The cooperation between webs 12 and 13 on the head, and 9 and 10 on the cylinder makes possible proper fitting thereof. The screws 16 are accessible from the side without the necessity of cutting away any of the fins above and below them and are tightened one after the other, drawing down the head over the cylinder. Inasmuch as the contact between webs 12, 13 and 9, 10 is at an angle to the contact between 8 and 11, the danger of the head being tipped to one side during the tightening of screw 16 is avoided. The head is in direct contact with the cylinder, the necessity of providing gaskets or other forms of packing being avoided. Owing to this arrangement heat developed in the head is dissipated, not only through its fins but also through the cylinder 1. Another important feature of the present arrangement of attaching the cylinder head is that no large bosses need be provided at the points where the head and the cylinder 25 are bolted together. Large sections of the cooling surface would have to be cut away to make such bolts accessible. Furthermore, the casting of the head and the cylinder would be more difficult on account of the unequal thickness of the various parts which, of course, do not cool at the same rate, resulting in distortion of the casting.

The sloping wall 11 of the head forms for a space one of the side walls of the compression chamber 17 and is surrounded by an annular chamber 18 bounded by three cooling fins 19 forming part of the cooling system of the cylinder head. The fins 19 are not of the same width all around the cylinder head. At one point two of these fins are elongated into fins 20 and 21 which terminate in a seat 22. The annular passageway 18 opens into a chamber formed by the fins 20 and 21. Attached to the seat 22 is a casting 23 connected with the gasoline tank at 24. The flow of gasoline through 24 and a vertical bore 25 into the casing 23 is controlled by means of a needle valve 26 controlled in turn by a float 27 responsive to the level of the liquid in casing 23. 28 is a draining plug for the casing 23. Gasoline from the casing 23 passes through a channel 29 controlled by another needle valve 30 through a tube 31. The tube 31 is set into the casing 23 and is surrounded by a second tube 32. The cylindrical space between the concentric tubes 32 and 31 is in communication with the outside atmosphere through a valve 33, which is provided with the usual vertical and horizontal perforations (not shown). The ends of tubes 31 and 32 are tapered and in close proximity to each other so as to produce the well known Venturi tube effect. These tubes project within the chamber afforded by the fins 20 and 21

and send a spray of gasoline and air mixture right and left through the passageway 18 around the head 3. Access may be had to the float 27 by removing a cover plate 40 which is attached to a boss of the casing by means of screw 41.

The top of the cylinder head 3 is provided with two perforations 45 and 46 which serve as seats for intake and exhaust valves 36, 42, the stems 38, 43 of which project through perforations 50 and 51 provided in bosses 52 and cast integral with the cylinder head. The valve stems project with a housing 62 attached to the head at 54 and are controlled by springs 37, 44, cams 39, 47 on rocker arms like 48 and push rod 61 in the well-known manner. It will be noted that the valves are of relatively large diameter permitting complete scavenging action which is facilitated also by their location in the head. It is necessary that a uniform section of iron and free circulation of air be permitted around the valve seats, particularly the seat 45 for the exhaust valve which is subjected to the higher temperatures. The present head is so designed that the section of iron 64 between 45 and 46 (Fig. 1) is substantially equal to the total iron on the other sides of these valve seats. Furthermore, the cooling effect of air passing above 64 between webs 53 is about the same as that of air passing between webs 55 and fins 4 adjacent to the other sides of the valve seats.

The valves, and particularly the exhaust valve, is further protected from injury by heat by the provision of two spark plugs and by the location thereof. These spark plugs 7 are placed at diametrically opposite points of the head between the two valves. The longitudinal axes of the spark plugs are at an angle to the vertical axis of the cylinder. The spark plugs are simultaneously actuated and owing to the manner in which they are placed in the head, the flames of the explosion will uniformly surge around the chamber 17. With a single spark plug, most of the flame is sucked towards the exhaust port, resulting in burned-out or warped valves.

In order to make room for valves 36, 42 of sufficiently large diameter and also to have sufficient space between them for the free circulation of air, the head 3 is so shaped that the length on the axis of the valves is greater than the diameter of the cylinder 1, and the mouth of the cylinder is flaring. In order, however, to reduce the compression chamber within the head to the required volume, the head is constructed with an oval section tapered outwardly. This will be clear from Fig. 2, which is a vertical cross-section taken between the two valves. A further advantage of the present construction resides in that the valves are in alignment with the vertical axis of the

cylinder, whereby the machining and grinding operation are facilitated and the connection with the cam shaft is simplified.

Diametrically opposite fins 20, 21 the fins 5 surrounding head 3 take the form of a webbing 55 enclosing cooling passages 56, and the lower face of which is curved, forming the roof of a chamber 57 enclosed on the lower side by a fin 58 of the cylinder head. 10 It should be noted in this connection that the entire head, including the fins and webbings, is cast of one piece. The fin 58 is curved upward and, together the webbing 55, affords a seat for a throttle-controlled 15 gas and air mixing device. This device consists of a sleeve 70 provided with a flange 71 which sets on a gasket 72 provided in the seat, the positioning of the sleeve 70 with respect to the member 58 being determined 20 by a dowel pin (not shown) projecting from the sleeve and cooperating with a suitably located hole in the member 58. The sleeve is provided with two perforations 74 and 75. The sleeve 70 fits within a longitudinal bore 25 provided in a cylindrical casting 77. The casting 77 is provided with a short horizontal shaft 78 and with three annular ridges 79, 80 and 81, forming the side walls of two annular chambers 82 and 83. The wall 30 of the cylinder 77 is provided with two perforations 84 and 85 which connect the chamber 76 with the annular chambers 82 and 83, respectively. The diameter of the perforations 84 and 85 is the same as that of perforations 74 and 75 in the sleeve 70 and are 35 so located that when the sleeve is enclosed by casting 77, the two sets of holes will register. Short sleeves 86, the inside diameter of which is the same as that of 84 and 85, and which project above the bottom of chambers 82 and 83, are held in enlargements of apertures 84 and 85. The cylinder 77 is enclosed by and fastened to a cylinder 40 87. A blade 60 projects radially from cylinder 77 parallel with its longitudinal axis and opposite the apertures 84, 85. The blade 60 is substantially coextensive with cylinder 77 and projects the full height of chambers 82, 83. The walls of cylinder 87 are 45 provided with two pairs of diametrically opposite perforations 88 and 89, the diameter of which is the same as the width of the annular chambers 82 and 83. Furthermore, the cylinder 87 is provided with two pairs 50 of diametrically opposite perforations 90 and 91. The centers of perforations 88, 89 and 90, 91 are in alignment, but the smaller perforations are not provided exactly midway between the two pairs of larger perforations. The distance between the centers of perforations 90 and 88 is 79°, and between the centers of 55 88 and 91, 101°.

The cylinder 87 fits within a chamber enclosed by a cylinder 92. The cylinder 92 is provided with two pairs of perforations

93 and 94 which are coincident with and of the same size as perforations 88 and 89 of cylinder 87. The cylinder 92 terminates in a flange 95 engaging a gasket 96 provided on a circular seat 97 provided on casting 49 70 forming part of cylinder head 3. The end wall 95 of the cylinder 92 is perforated and shaped to form a bearing through which the shaft 78 of sleeve 77 projects.

The mixing device is assembled by first 75 assembling 70, 77, 87 and 92, and then positioning it in seat member 59 by means of pin (not shown), whereupon the whole assembly is fastened into place by four screws 100a-d, by means of which flange 95 of cylinder 92 is held against seat 97. The heads of screws 100c and d are countersunk in the flange, but the heads of 100a and b project from the flange. 70 and 92 are rigidly held 80 against the head 3, and 77, 87 are rotatable 85 with respect thereto.

A casting 101 seated on shaft 78 encloses a coiled spring 102 wound around the casting. One end of spring 102 terminates in a loop 103 and the other end in an L-shaped 90 tail 104. The casting 101 is provided with a ridge 105 from which two bosses 106 and 107 project. The ridge 105 is provided with a plurality of slanting notches 108 for receiving the stem of spring 102. The annular chamber 109 formed by casting 101, 105 is enclosed by a second casting 110 which is held against shaft 78 by means of a set screw (not shown). The casting 110 carries 95 fan blades 112 and 112a fastened thereto by means of screws 113. The boss 106 has rib 123 adapted to engage the heads of screws 100a and 100b and thus limit the rotation of 101 between these screw heads. The movement of the casting may be brought about 100 by means of a wire 119 supported on a boss 120 of the cylinder head and controlled in 105 turn by the operator's throttle lever (not shown). The wire 119 is attached to the boss 106 by means of a screw 118.

The rotation of 101 is transmitted to 110 by means of the wire 102, the tail 104 of which projects within an aperture in casting 110. The casting 110 is positioned with respect to the casting 101 by means of a pin 120 115 projecting from 110 and engaging the sloping end of a screw 115 held in boss 107 of casting 101.

Attached to the casting 131 is a plate 130. The cylinder 1 is bolted to this casting 131 120 at 132, 133, 134 and 135. The two push rods extend through perforations 138 and 139 in the casting 131. The casting is provided 125 with ridges forming substantially two parallelograms 140 and 141 interconnected by means of a narrow ridge 142, and ridges 143 and 144 terminating in a point 145 midway between the channel 205 formed by 140 and 141. A plate 146 is fastened to the casting 131 by means of screws 147 engaging the 130

ridges. The plate extends to the cylinder and is provided with two perforations 148 and 149. The plate 146 is raised around the perforation 149 to form a neck 150 on which 5 fits pipe 151. The other end of pipe 151 is fastened by means of a screw 152 to a seat 59 formed in head 3. The opening 148 coincides with an opening 153 in a casting 154 on which is mounted at 155 a blower 156 10 suitably carried in ball bearings and driven by means of a belt 157 from the crankshaft or other suitable source.

The operation of the engine will now be described.

15 Assuming that the piston 200 in cylinder 1 is just descending, gasoline will be drawn from tank 201 through pipe 202 and thence through channels 24, 25 past the needle valve 26 through channels 29, past needle valve 30, 20 through tube 31 at the nozzle of which it will be mixed with air rushing in past the needle valve 33 through the tube 32. The particles of gasoline suspended in the air will be sent in a right-hand and left-hand 25 direction through the annular chamber 18, and by coming thus into contact with the hot cylinder head, will be completely vaporized by the time they reach chamber 57. Liquid particles that reach chamber 57 will 30 flow back into contact with the cylinder head, owing to the slope at 58. Assuming that the throttle is wide open, air drawn in by the blower 156 is streaming into the channels 203, 204, and then turns at right angles 35 into the channel 205 and through 153 into the outside atmosphere. Part of the air drawn through channel 205 will be diverted up through the pipe 151, owing to the suction exerted by the descending piston. Inasmuch as the passage of air from the outer 40 atmosphere through 205 and then 151 is twice interrupted at substantially right angles, hard particles such as sand that might be suspended in the air will, by their 45 own momentum, continue to travel, drawn by the suction of the blower through channel 205 and 153. Such hard particles are aided in their tendency to travel through the channel 205 by the fact that the channel 153 is 50 tapering, whereby it acts as a Venturi tube and accelerates the movement of such heavy particles. This arrangement constitutes an air cleaner which, without the use of any 55 screens, felt pads or the like, that need constant cleaning and adjustment, insures that air deprived of all hard, gritty substances that might injure the cylinder walls, pass through the tube 151. Light particles, such as scraps of grass that might be drawn 60 through 151, will of course be destroyed by combustion and cannot, at any event, injure the cylinder.

Assuming that the throttle is wide open 65 and that therefore the carburetor is in the position illustrated in Fig. 4, air drawn up

through openings 94 and 89 is divided by rib 60 into two equal columns and passes through annular chambers 82 and 83 and thence upwards through openings 88 and 93. This air is mixed at the nozzle of sleeves 86 70 with gas drawn through openings 74, 75 and 84, 85. The intake valve 36 is opened at this time and the mixture of gasoline and air is sucked into the cylinder. In the well-known manner, upon the return movement 75 of the piston 200, the mixture is compressed in the cylinder, the valve 36 being closed. At the proper instant a spark is produced at the points of the spark plugs and the compressed gasoline mixture is exploded, causing the return movement of the piston 200. In the well-known manner, the exhaust valve 42 is opened at this time and the dead gases are permitted to escape through the exhaust port 63. 80

When the operator desires to slow down the engine he will press down wire 119, causing thus the casting 101 to rotate in a counter-clockwise direction (see Fig. 6). The rotation of casting 101 is transmitted 90 through the agency of spring 102 to the casting 110 and the latter, through the agency of the shaft 78 to which it is attached, will cause the rotation of sleeve 77 and cylinder 87 (see Figs 4 and 5). The further the shaft 95 78 is rotated, the smaller will be the aperture through which air can enter at 89 and 94. However, at the same time the opening through which gas can escape at 74 is correspondingly restricted, insuring thus that the ratio between gas and air, as predetermined by the location and size of the various apertures, be retained irrespective of the total quantity of mixture sucked into the cylinder. The air that is mixed with the vaporized 100 gasoline is not preheated, thereby the efficiency of the engine is materially increased. 105

As will be apparent from Fig. 5, the purpose of the blade 60 is to insure that when the air intake port is restricted by the manipulation of the throttle, most of the air be forced to pass to the right of sleeve 86, insuring thus proper intermixing of the two gases. The blade 60 offers sufficient resistance to the passage of air through what 110 would be otherwise the wider channel. 115

If it is desired to stop the motor, then the operator continues to depress wire 119, causing the clockwise movement of 77 and 87 (Fig. 5). A point will be reached where 120 both openings 94 and 93 are closed and neither gas nor air is delivered to the engine. However, on account of the momentum of the flywheel, the engine might continue to operate, causing the ignition of residual 125 gases. In order to avoid the necessity of brakes, ignition controlling switches or the like, that would be otherwise necessary to bring the engine to a dead stop, the device is so arranged that by continuing the move- 130

ment of the throttle in the same direction past the last mentioned closed position, the small apertures 90 and 91 will register with the openings 93 and 94, drawing air through such openings into channels 82, 83 and thence into the cylinder head. Inasmuch as the aperture 74 is now closed by the wall of 77, no gas is delivered to the cylinder. This will prevent further functioning of the engine.

Air drawn by the blower 156 over the cooling surfaces of the cylinder and the head will impinge upon fan blades 112 and 112a. When the air thus drawn past the blades 112 and 112a attains a certain velocity, it turns, through the agency of these blades, the casting 110 and therethrough 87 and 77 in a clockwise direction (Figs. 4 and 5), shutting off the gas supply to the cylinder.

The purpose of this arrangement is to prevent unnecessary racing of the engine which would occur, for instance, when the load is suddenly taken off the engine.

What I claim is:

- 25 1. In a gasoline engine, a cylinder having cooling fins, a cylinder head having cooling fins and in contact with said cylinder, and screws for holding said head on said cylinder the longitudinal axes of which are at substantially right angles to the vertical axis of said cylinder.
- 30 2. In a gasoline engine, a cylinder having cooling fins projecting therefrom, a rim projecting therefrom, a cylinder head, and clamping screws projecting through the lower part of said head into engagement with one of said fins.
- 35 3. In a gasoline engine, a cylinder head having a seat on the cylinder of the engine which consists of two rings fastened to the cylinder, the contacting surfaces of said rings being at different angles to the vertical axis of the cylinder.
- 40 4. In a gasoline engine, a cylinder head having a seat on the cylinder which consists of three rings fastened to the cylinder, the contacting surface of one ring being at an angle and the contacting surfaces of the other two rings being substantially parallel to the vertical axis of the cylinder.
- 45 5. In a gasoline engine, a cylinder head having a seat on the cylinder which consists of a plurality of rings integral with the cylinder, the contacting surface of one ring being at an angle and the contacting surfaces of the other rings being parallel to the vertical axis of the cylinder.
- 50 6. In a gasoline engine, a cylinder having a bevelled rim, a cylinder head having a sloping wall engaging said rim, a skirt on said head depending below said sloping wall,

and projections on said cylinder with which said skirt contacts.

7. In a gasoline engine, a cylinder head having a seat on a cylinder which consists of cooling rings fastened to the cylinder, and cooling fins projecting from the cylinder head the bases of which contact with said rings.

8. In a gasoline engine, a cylinder head having a seat on a cylinder which consists of cooling rings integral with the cylinder, and cooling fins projecting from the cylinder head and forming continuations of said rings.

9. In a gasoline engine, a cylinder having a seat on the engine which consists of two rings integral with the cylinder, the contacting surfaces of said rings being respectively at an angle and parallel to the vertical axis of the cylinder, and screws projecting through said cylinder head and engaging the parallel ring.

10. In a gasoline engine, a cylinder, a plurality of fins projecting therefrom, said fins being of gradually increasing width toward the mouth of the cylinder, a bevelled fin projecting at the end of the cylinder, two relatively short fins having straight ends projecting from the cylinder below said bevelled fin, a cylinder head, fins projecting therefrom, a sloping inside wall for said head contacting with said bevelled fin on the cylinder, two fins held by webs to said head and contacting with said two relatively short fins on the cylinder, apertures in some of said webs, and screws projecting through said apertures and engaging the lower surfaces of one of said relatively short fins, the longitudinal axes of said screws being at substantially right angles to the vertical axis of said cylinder.

11. In a gasoline engine having a valve enclosing box, spark plugs, gasoline vaporizer, carburetor and air intake port, a single casting comprising intake and exhaust valve seats, a seat for the valve enclosing box, seats for the spark plugs for the gasoline vaporizer, carburetor and air intake port, and air cooling fins.

12. In an internal combustion engine, a cylinder having a flaring mouth, a cylinder head, two valves therein, the length of said head on the axis of the valves being greater than the diameter of the cylinder, its width narrower than its length and its section being outwardly tapering.

In testimony whereof, I have signed my name to this specification, this 19th day of May, 1924.

WILLIAM F. SMITH.
